(57) **CLAIM**

The ornamental design for a deck-mount water spout, as shown and described.

DESCRIPTION

FIG. 1 is a top, front, left-side perspective view of a deck-mount water outlet spout showing my new design;

FIG. 2 is a bottom plan view thereof;

FIG. 3 is a top plan view thereof;

FIG. 4 is a left side elevational view thereof, the right side elevational view being mirror symmetrical thereto;

FIG. 5 is a front elevational view thereof; and,

FIG. 6 is a rear elevational view thereof.
